DESIGN FOR A CAN OR SIMILAR ARTICLE

William B. McDonald, San Francisco, Calif.

Application October 31, 1938, Serial No. 80,788

Term of patent 7 years

To all whom it may concern:

Be it known that I, William B. McDonald, a citizen of the United States and a resident of the city and county of San Francisco, State of California, have invented a new, original, and ornamental Design for a Can or similar Article, of which the following is a specification, reference being had to the accompanying drawing, forming part thereof.

Both ends of the can or similar article are alike, and the opposite side to that shown in Figure 1 is uniform with the left half of the showing of Figure 1.

I claim:

The ornamental design for a can or similar article substantially as shown and described.

WILLIAM B. McDONALD.
